CLAIM

The ornamental design for a fluid control device, as shown and described.

DESCRIPTION

FIG. 1 is a perspective view of our ornamental design for a fluid control device.

FIG. 2 is a top view of our design shown in FIG. 1.

FIG. 3 is a right-side plan view of our design shown in FIG. 1.

FIG. 4 is a front elevation view of our ornamental design for a fluid control device.

FIG. 5 is a section 5-5 view which more clearly brings out elements of our claimed design shown in FIG. 1.

FIG. 6 is a left-side plan view of our design shown in FIG. 1; and,

FIG. 7 is a bottom view of our design shown in FIG. 1. The use of broken lines indicates that the portion of the article depicted in broken lines forms no part of the design and is not to indicate the relative importance of parts of a design.
